SUSPENDED CEILING CLIP

Martin L. Lydard, Ellicott City, Md., assignor to Eastern Products Corporation, Baltimore, Md., a corporation of Maryland

Filed Dec. 1, 1961, Ser. No. 156,353
6 Claims. (Cl. 189—35)

The present invention relates to suspended ceiling construction and more particularly to a clip for use in such constructions.

In suspended ceiling constructions as commonly used, a series of spaced parallel runners are suspended from primary ceiling members and are used to support the acoustical tiles or other sheets or panels which make up all or a major portion of the ceiling as viewed from the room beneath. The runners are generally formed with a vertical web portion and horizontal flanges at the top and bottom, the top flanges abutting against the primary ceiling members and the bottom flanges serving to support the acoustical tiles or other sheets or panels. The runners may be formed as nailing bars having a vertical web and horizontal flanges at the top.

Steel wire clips of various shapes have heretofore been used for attaching runners to the primary ceiling members. The present invention is concerned with providing a novel and improved clip for use in a construction in which the primary ceiling members each have a vertical surface and two horizontal surfaces and are usually in the form of elongated channels having vertically disposed webs and in which the runners have vertical webs with horizontal flanges extending laterally from both sides of the top of the web.

Suspended ceiling clips should be easy to install with regard to both the time and effort involved. The clips should also be reliable; that is to say, once installed they should not easily be dislodged, even when subjected to substantial vibration or other mechanical stresses. Since suspended ceiling clips must be relatively inexpensive, it can be expected that substantial dimensional variations will occur during manufacture; but, despite such variations, the clips should perform satisfactorily. Another important requirement for such clips is that they afford as much stability as possible to the ceiling construction.

A principal object of the invention has been to provide a novel and improved ceiling suspension clip.

More particularly, it has been an object of the invention to provide such a clip which fulfills the foregoing and other requirements more satisfactorily than has been possible with clip designs previously used.

Other and further objects, features and advantages of the invention will appear more fully from the following description taken in connection with the appended drawings, in which:

FIG. 1 is a top plan view of a ceiling suspension clip embodying the invention;

FIG. 2 is a side elevational view of the clip of FIG. 1;

FIG. 3 is a front elevational view of the clip of FIG. 1;

FIG. 4 is a side elevational view, partly in cross section, showing the clip of FIG. 1 installed in a ceiling system; and

FIG. 5 is a cross-sectional view taken along the line 5—5 of FIG. 4.

Referring now to the drawings, the clip of the invention is shown in FIGS. 1-3 and might be made from a single length of hard drawn spring wire or the like. Typically, the wire diameter might be .1205 inch. The clip has a top portion 10, a generally vertical intermediate portion 11, and a bottom portion 12, each constituted by various legs formed by bending the wire stock.

As shown in FIGS. 4 and 5, the clip serves to suspend

2

a runner 13 from a ceiling channel member 14. The runner 13, which may be formed from a single strip of steel or other suitable material, has a vertical web 15, horizontal flanges 16 and 17 extending laterally from the top of web 15 at respective sides thereof and horizontal flanges 18 and 19 extending laterally from the bottom of web 15 at respective sides thereof. The ceiling channel member 14 has a vertical web 20 and horizontal flanges 21 and 22 extending laterally from the top and bottom, respectively, of web 20 at one side thereof.

When installed, the channel member 14 and the runner 13 are disposed so that their axes form a right angle, with the upper surfaces of flanges 16 and 17 abutting the undersurface of flange 22. The runner 13 is supported from and is maintained in position beneath channel member 14 by the clip of the invention.

The lower portion 12 of the clip is formed by legs 23 and 24 each of which has a free end formed by the respective ends of the wire stock. The free end of the leg 23 contacts the undersurface of flange 16 and the leg is inclined downwardly and extends at an angle with respect to the axes of the runner 13 and channel member 14. Similarly, the free end of the leg 24 contacts the undersurface of flange 17 and the leg is inclined downwardly and extends at an angle with respect to the axes of the runner 13 and channel member 14. The free ends of the legs 23 and 24 preferably touch each other before installation and lie adjacent the web 15 after installation.

The legs 23 and 24 are joined to legs 25 and 26, respectively, by curved bends 27 and 28, respectively, which might have, for example, a $\frac{1}{8}$ inch radius. The bends 27 and 28 are disposed approximately beneath the web 15 and outwardly of the free ends of the flanges 16 and 17, respectively. The legs 25 and 26 comprise the clip intermediate portion 11 and are disposed so as to lie substantially vertically and adjacent the outer surface of web 20. The legs 25 and 26 are inclined inwardly in a vertical plane toward the plane of web 15. At their upper ends the legs 25 and 26 are adjacent the upper surface of flange 21 and are separated from each other by an appreciable distance which is substantially less than the combined widths of flanges 16 and 17. For example, if flanges 16 and 17 have a combined width of $\frac{3}{4}$ inch and if the height of channel member 14 is $1\frac{1}{16}$ inches, the spacing between the upper ends of legs 25 and 26 might be $\frac{7}{32}$ inch.

The upper ends of legs 25 and 26 are joined to legs 29 and 30, respectively, by relatively short radius bends 31 and 32, respectively. The bends 31 and 32 might be formed, for example, with a radius of $\frac{3}{64}$ inch. The height of the legs 25 and 26 is selected so that the inner center of the bends 31 and 32 will lie slightly above the upper surface of flange 21.

The legs 29 and 30 are inclined outwardly with respect to the plane of web 15 and are inclined slightly downwardly with respect to the upper surface of flange 21. Thus, contact between the legs 29 and 30 and the upper surface of flange 21 will occur primarily adjacent the front edge of flange 21, i.e., the free end of flange 21.

The legs 29 and 30 are joined to legs 33 and 34, respectively, by bends 35 and 36, respectively. The bends 35 and 36 are formed with a relatively large radius, e.g., $\frac{5}{32}$ inch. The legs 33 and 34 are inclined inwardly with respect to the plane of web 15 and are inclined slightly downwardly with respect to the upper surface of flange 21. The legs 33 and 34 are joined by a bend 37 which might have for example, a radius of $\frac{1}{8}$ inch.

The downward inclinations of legs 29, 30, 33 and 34 are relatively slight, but the resulting difference in elevation between the bottom of the center of bend 37 and the inner center of bends 31 and 32 is substantial, and might be, for example, $\frac{5}{32}$ inch.

The horizontal spacing between the inner center of bend 37 and the inner surfaces of legs 25 and 26 is slightly greater than the width of flange 21. The legs 29, 30, 33 and 34 and their joining bends comprise the clip upper portion 10 and have a generally heart shape, as shown in FIG. 1.

To install the clip, the runner 13 and channel member 14 are brought into position as shown in FIGS. 4 and 5. The clip is sprung on over the flanges 16 and 17 of the runner and brought into contact with the channel member. Because of the downward inclination of the upper portion 10 of the clip, the legs 33 and 34 and the bend 37 will not readily pass over the top of flange 21. To cause the legs 33 and 34 and the bend 37 to pass over the top of flange 21, a substantial force must be exerted, as by pushing with the thumbs on legs 25 and 26 while holding the channel member with the fingers. This substantial force causes the legs 33 and 34 and the bend 37 to move upwardly against the spring action of the clip material. Bending of the legs 29 and 30 and of the legs 23 and 24 against the spring action of the clip material also aids in permitting this clearance. When the inner end of bend 37 clears the edge of flange 21, the legs 33 and 34 and the bend 37 spring downwardly so that the inner center of bend 37 lies at the height of flange 21. Hence, any tendency for the clip to be dislodged is overcome by contact between bend 37 and the adjacent edge of flange 21.

As mentioned above, installation of the clip also requires a small upward bending of legs 29 and 30 and a small bending of legs 23 and 24. When the upper portion of the clip springs down into the position shown in FIG. 4, the bending of the legs 29 and 30 and of the legs 23 and 24 is not completely relieved. Hence, these legs are maintained under some spring tension which serves to hold legs 29 and 30 in tight contact with the upper surface of flange 21 and also the free ends of legs 23 and 24 in tight contact with the undersurface of flanges 16 and 17, respectively.

In constructing a complete ceiling, the runner 13 will be suspended from at least two, and generally more, parallel ceiling channel members by the use of clips identical to that shown.

An important advantage secured by the clip of the invention results from the permanent spring tension in the clip after installation. Because of this tension, the runner and beam will be held in tight contact and will not tend to come apart, as can happen when some other types of clips are used or when a simple twisted wire suspension is used.

While the invention has been described in connection with a specific embodiment thereof and in a specific use, various modifications thereof will occur to those skilled in the art without departing from the spirit and scope of the invention as set forth in the appended claims.

What is claimed is:

1. A wire clip for use in attaching an elongated runner to an elongated ceiling member, said runner and said member extending transversely with respect to each other, said ceiling member having an axially extending outer vertical surface and axially extending horizontal flange surfaces projecting laterally in one direction from said vertical surface at the top and bottom thereof, said runner having an axially extending vertical web and axially extending horizontal flange surfaces projecting laterally in opposite directions from the upper end of said vertical web, the upper surfaces of said runner flanges being adapted to be in surface contact with said lower flange surface of said member; said wire clip being formed from a single length of stiff wire and comprising a lower portion having a first pair of legs each located at a respective end of said length of wire and each being adapted to contact the undersurface of a respective one of said runner flanges, an intermediate portion having a second pair of legs each joined at one end to a respective one of the legs of said first pair and being adapted to lie adjacent said vertical

surface of said ceiling member, said first pair of legs extending generally inwardly and upwardly from said second pair of legs and, when said clip is installed, extending generally in one direction along the axis of said runner, and an upper portion formed by a series of bends in said wire and being joined at each end to the upper end of a respective one of said legs of said second pair, said upper portion extending generally in said one direction and being inclined downwardly from said second pair of legs so that said upper portion is adapted to contact the upper flange surface of said ceiling member when said clip is installed, said upper portion extending beyond the outer edge of said upper flange surface of said ceiling member and having an area disposed adjacent the outer edge of said upper flange surface when said clip is installed, the combined heights of said first and second portions being substantially equal to the combined heights of said ceiling member and said runner flanges, the downward inclination of said upper portion being sufficient to require a substantial springing of said clip for installation thereof.

2. A wire clip for use in attaching an elongated runner to an elongated ceiling member, said runner and said member extending transversely with respect to each other, said ceiling member being a channel having an axially extending outer vertical surface and axially extending horizontal flange surfaces projecting laterally in one direction from said vertical surface at the top and bottom thereof, said runner having an axially extending vertical web and axially extending horizontal flange surfaces projecting laterally in opposite directions from the upper end of said vertical web, the upper surfaces of said runner flanges being adapted to be in surface contact with said lower flange surface of said member; said wire clip being formed from a single length of spring wire and comprising a lower portion having a first pair of legs each located at a respective end of said length of wire and each being adapted to contact the undersurface of a respective one of said runner flanges at a corresponding point adjacent said runner web, an intermediate portion having a second pair of legs each joined at one end to a respective one of the legs of said first pair and being adapted to lie adjacent said vertical surface of said ceiling member, said first pair of legs extending generally inwardly and upwardly from said second pair of legs and, when said clip is installed, extending generally in one direction along the axis of said runner, and an upper portion having a generally heart-like shape formed by a series of bends in said wire and being joined at each end to the upper end of a respective one of said legs of said second pair, said upper portion extending generally in said one direction and being inclined downwardly from said second pair of legs so that said upper portion is adapted to contact the upper flange surface of said ceiling member when said clip is installed, said upper portion extending beyond the outer edge of said upper flange surface of said ceiling member and having an area forming the apex of said heart shape disposed adjacent the outer edge of said upper flange when said clip is installed, the combined heights of said first and second portions being substantially equal to the combined heights of said ceiling member and said runner flanges, the downward inclination of said upper portion being sufficient to require a substantial springing of said clip for installation thereof, the spring tension in said clip being only partially relieved when said clip is fully installed.

3. A wire clip for use in attaching an elongated runner to an elongated ceiling member, said runner and said member extending transversely with respect to each other, said ceiling member having an axially extending outer vertical surface and axially extending horizontal flange surfaces projecting laterally in one direction from said vertical surface at the top and bottom thereof, said runner having an axially extending vertical web and axially extending horizontal flange surfaces projecting laterally in opposite directions from the upper end of said vertical

web, the upper surfaces of said runner flanges being adapted to be in surface contact with said lower flange surface of said member; said wire clip being formed from a single length of stiff wire and comprising:

(1) a lower portion comprising a first pair of legs each located at a respective end of said length of wire and each being adapted to contact the undersurface of a respective one of said runner flanges at a corresponding point adjacent said runner web, the legs of said first pair, when said clip is installed, each extending downwardly and outwardly to a point substantially beneath said vertical surface of said member and outward of the outer edges of the respective flanges of said runner;

(2) an intermediate portion comprising a second pair of legs extending upwardly in a generally vertical plane and being joined at the lower ends thereof to respective legs of said first pair by respective ones of a first pair of bends in said wire, the legs of said second pair being inclined inwardly toward each other, said legs of said second pair being adapted to lie adjacent said vertical surface of said ceiling member and the upper ends of said legs of said second pair being substantially at the height of said upper flange surface of said ceiling member when said clip is installed; and

(3) an upper portion comprising a third pair of legs each connected at the rear end thereof to a respective leg of said second pair by respective ones of a second pair of bends in said wire, the legs of said third pair of legs lying in a plane inclined slightly downwardly so that when said clip is installed the legs of said third pair contact said upper flange surface of said ceiling member, said legs of said third pair being substantially longer than the width of said upper flange surface of said ceiling member whereby the forward ends of the legs of said third pair extend substantially beyond the end of said upper flange surface of said ceiling member when said clip is installed, a fourth pair of legs each connected at the rear end thereof to a respective leg of said third pair of legs by respective ones of a third pair of bends in said wire, the forward ends of the legs of said fourth pair being joined by a fourth bend in said wire, the legs of said fourth pair of legs lying in a plane inclined slightly downwardly and extending in the opposite direction from the legs of said third pair of legs, the length of the legs of said fourth pair and the inclination of the planes of said third and fourth pairs of legs being selected so that said fourth bend lies adjacent the inner edge of said upper flange surface of said ceiling member when said clip is installed, said clip having sufficient springiness to permit the legs and bends of said upper portion to be carried over said upper flange surface of said ceiling member when said clip is installed.

4. A wire clip for use in attaching an elongated runner to an elongated ceiling member, said runner and said member extending transversely with respect to each other, said ceiling member having an axially extending outer vertical surface and axially extending horizontal flange surfaces projecting laterally in one direction from said vertical surface at the top and bottom thereof, said runner having an axially extending vertical web and axially extending horizontal flange surfaces projecting laterally in opposite directions from the upper end of said vertical web, the upper surfaces of said runner flanges being adapted to be in surface contact with said lower flange surface of said member; said wire clip being formed from a single length of spring wire and comprising:

(1) a lower portion comprising a first pair of legs each located at a respective end of said length of wire and each being adapted to contact the undersurface of a respective one of said runner flanges at a correspond-

ing point adjacent said runner web, said points of contact of the legs of said first pair having an axial location with respect to said runner intermediate the limits of contact between said runner and said member, the legs of said first pair, when said clip is installed, each extending downwardly and outwardly to a point substantially beneath said vertical surface of said member and outward of the outer edges of the respective flanges of said runner;

(2) an intermediate portion comprising a second pair of legs extending upwardly in a generally vertical plane and being joined at the lower ends thereof to respective legs of said first pair by respective ones of a first pair of rounded bends in said wire, the legs of said second pair being inclined inwardly toward each other but being separated by a substantial distance at the upper ends thereof, said legs of said second pair being adapted to lie adjacent said vertical surface of said ceiling member and said upper ends of said legs of said second pair being substantially at the height of said upper flange surface of said ceiling member when said clip is installed; and

(3) an upper portion comprising a third pair of legs each connected at the rear end thereof to a respective leg of said second pair by respective ones of a second pair of rounded bends in said wire, the legs of said third pair of legs lying in a plane inclined slightly downwardly and being inclined outwardly so that when said clip is installed the legs of said third pair contact said upper flange surface of said ceiling member and diverge outwardly from the plane of said runner web, said legs of said third pair being substantially longer than the width of said upper flange surface of said ceiling member whereby the forward ends of the legs of said third pair extend substantially beyond the end of said upper flange surface of said ceiling member when said clip is installed, a fourth pair of legs each connected at the rear end thereof to a respective leg of said third pair of legs by respective ones of a third pair of rounded bends in said wire, the forward ends of the legs of said fourth pair being joined by a fourth rounded bend in said wire, the legs of said fourth pair of legs lying in a plane inclined slightly downwardly and being inclined inwardly toward each other and extending in the opposite direction from the legs of said third pair of legs, the length of the legs of said fourth pair and the inclination of the planes of said third and fourth pairs of legs being selected so that said fourth rounded bend lies adjacent the inner edge of said upper flange surface of said ceiling member when said clip is installed, said clip having sufficient springiness to permit the legs and bends of said upper portion to be carried over said upper flange surface of said ceiling member when said clip is installed.

5. A wire clip for use in attaching an elongated runner to an elongated ceiling member, said runner and said member extending transversely with respect to each other, said ceiling member having an axially extending outer vertical surface and axially extending horizontal flange surfaces projecting laterally in one direction from said vertical surface at the top and bottom thereof, said runner having an axially extending vertical web and axially extending horizontal flange surfaces projecting laterally in opposite directions from the upper end of said vertical web, the upper surfaces of said runner flanges being adapted to be in surface contact with said lower flange surface of said member; said wire clip being formed from a single length of spring wire and comprising:

(1) a lower portion comprising a first pair of legs each located at a respective end of said length of wire and each being adapted to contact the undersurface of a respective one of said runner flanges at a corresponding point adjacent said runner web, said points of contact of the legs of said first pair having an axial location with respect to said runner intermediate the

limits of contact between said runner and said member, the legs of said first pair, when said clip is installed, each extending downwardly and outwardly to a point substantially beneath said vertical surface of said member and outward of the outer edges of the respective flanges of said runner;

- (2) an intermediate portion comprising a second pair of legs extending upwardly in a generally vertical plane and being joined at the lower ends thereof to respective legs of said first pair by respective ones of a first pair of rounded bends in said wire, the legs of said second pair being inclined inwardly toward each other but being separated by a substantial distance at the upper ends thereof, said legs of said second pair being adapted to lie adjacent said vertical surface of said ceiling member and said upper ends of said legs of said second pair being substantially at the height of said upper flange surface of said ceiling member when said clip is installed; and
- (3) an upper portion comprising a series of bends in said wire forming a generally heart-shaped projection joined at the ends thereof to the respective upper ends of the legs of said second pair of legs, said heart-shaped projection extending beyond and being in contact with said upper flange surface of said ceiling member, said projection being inclined downwardly and proportioned so that the apex of said heart lies adjacent the inner edge of said upper flange surface of said ceiling member when said clip is installed, the downward inclination of said projection and the combined heights of said lower and intermediate portions being selected so that said wire clip must be substantially distorted to force said projection over the upper flange surface of said ceiling member during installation of said clip, said distortion and the resulting spring tension in said clip being only partially relieved when said clip is fully installed whereby said clip retains said runner and said ceiling member in tight contact with each other.

6. A wire clip for use in attaching an elongated runner to an elongated ceiling member, said runner and said member extending transversely with respect to each other, said ceiling member having an axially extending outer vertical surface and axially extending horizontal flange surfaces projecting laterally in one direction from said vertical surface at the top and bottom thereof, said runner having an axially extending vertical web and axially extending horizontal flange surfaces projecting later-

5

ally in opposite directions from the upper end of said vertical web, the upper surfaces of said runner flanges being adapted to be in surface contact with said lower flange surface of said member; said wire clip being formed from a single length of stiff wire and comprising:

- (1) a lower portion comprising a first pair of legs each located at a respective end of said length of wire and each being adapted to contact the under-surface of a respective one of said runner flanges at a corresponding point adjacent said runner web, the legs of said first pair, when said clip is installed, each extending downwardly and outwardly to a point substantially beneath said vertical surface of said member and outward of the outer edges of the respective flanges of said runner;
- (2) an intermediate portion comprising a second pair of legs extending upwardly in a generally vertical plane and being joined at the lower ends thereof to respective legs of said first pair by respective ones of a first pair of bends in said wire, said legs of said second pair being adapted to lie adjacent said vertical surface of said ceiling member and the upper ends of said legs of said second pair being substantially at the height of said upper flange surface of said ceiling member when said clip is installed; and
- (3) an upper portion comprising a series of bends in said wire and forming a projection joined at the ends thereof to the respective upper ends of the legs of said second pair of legs, said projection extending beyond and being in contact with said upper flange surface of said ceiling member, said projection having a re-entrant portion adapted to lie adjacent the inner edge of said upper flange surface of said ceiling member when said clip is installed, said projection having a downward inclination selected in combination with the combined heights of said lower and intermediate portions so that said wire clip must be substantially distorted to force said projection over the upper flange surface of said ceiling member during installation of said clip, said distortion and the resulting spring tension in said clip being only partially relieved when said clip is fully installed whereby said clip retains said runner and said ceiling member in tight contact with each other.
